UNITED STATES PATENT OFFICE.

EDMUND C. MOGFORD, OF BUCHANAN, AND FREDERICK W. BURGER, OF NILES, MICHIGAN, ASSIGNORS TO CLARK EQUIPMENT COMPANY, OF BUCHANAN, MICHIGAN, A CORPORATION OF MICHIGAN.

METHOD OF MAKING METAL WHEELS.

Application filed May 29, 1925. Serial No. 33,657.

Our invention relates to metal wheels of the spoke type, and has for its object to provide an improved wheel which will possess all the advantages of a cast metal wheel, and 5 at the same time will not be subject to the objections which have generally been encountered in the manufacture of such wheels. The nature of our invention, will clearly appear from the following description thereof 10 in connection with the accompanying drawings.

In the accompanying drawings, in which Fig. 1 is a side elevation showing the greater part of a wheel embodying our invention;

15 Fig. 2 is a partial vertical cross-section on line 2-2 of Fig. 1; and

Fig. 3 is a view similar to Fig. 2 showing a modified form.

Our improved wheel comprises a hub and 20 spoke structure cast as a unit, the spokes being hollow and provided at their outer ends with pads or laterally extended seats adapted to receive and support a felloe of conventional form. The casting that constitutes 25 the hub and spokes may be made of steel or malleable iron, and the felloe is a continuous steel band of outwardly facing channel sections preferably of the demountable type. Referring to the drawings,—4 indicates the 30 hub portion of the casting, 5 the spokes, and 6 the pads at the outer ends of the spokes which support the felloe 7. As shown at 8, the pads are chamfered at one side along their outer margins for a purpose that will 35 be presently stated. The spokes 5 are hollow and are open at their outer ends, and, as shown in Figs. 2 and 3, the felloe 7 is secured on said spokes by pressing portions of the felloe metal inwardly into the ends of the 40 spokes. This may be accomplished either by a drawing operation, as shown at 9 in Fig. 2, which is preferable because it closes the outer ends of the spokes, or it may be accomplished by a punching operation which perforates 45 the felloe and forms inwardly directed conical projections 10 which closely engage the outer ends of the spokes. By either of these expedients the felloe may be firmly secured 50 on the spokes, making the wheel substantially a unit. In constructing our improved wheel, the hub and spoke portion is first cast, the 55 chamfered portions 8 being formed in the casting operation. The casting, which is in the form of a spider of an outer diameter

larger than the inner diameter of the felloe by 55 an amount suitable to provide a pressed fit, is then pressed laterally into an ordinary felloe in the form of an endless band until it is properly centered, after which the felloe is drawn or punched radially inwardly over 60 the outer ends of the spokes to secure it firmly thereto. During this operation the wheel is supported against the drawing pressure by suitable supporting means applied to the spoke being operated upon beneath the pad 65 carried thereby, so that the pad serves as a head to prevent movement of the wheel. It also supports the felloe at the point of greatest pressure so that it is held true and its distortion is prevented, and besides it re-enforces 70 the outer end of the spoke so that it is not apt to be damaged under the great pressure to which it is subjected during the drawing operation. The spokes may be either circular or polygonal in cross-section, but the pads 75 6 are preferably made oblong to provide better support for the felloe especially during the punching or drawing operation, and also to stiffen and strengthen the wheel. The outer ends of the spokes are internally chamfered, so that the inwardly directed projections formed on the felloe by the drawing or 80 punching operation will fit them more closely. The pressing or indenting of the projections such as 9 and 10 after the felloe has been tensioned by the insertion of the spider serves 85 still further to tension the rim since the metal for such indentation is secured by stretching the web of the channel of which the felloe is constructed. The chamfering of the pads, as 90 above suggested, is to facilitate the forcing of the spider laterally into the felloe and prevent it from cutting into the felloe during that operation owing to the closeness of the fit. Thus the spider in being forced into the 95 rim has a wedging action that puts the rim under tension, making the wheel firm and rigid, and aiding in holding the parts tightly together. The felloe is thereby put under a high degree of tension and the spider likewise under a high degree of compression. 100

Our improved wheel possesses a number of advantages over prior constructions. For example, casting the spider separately is a much lighter operation than if the wheel were cast 105 complete, and therefore the work of making the casting can be done by one man instead of by two as is necessary where the complete

wheel is cast. Again, the machining cost is materially reduced, as where the wheel is cast complete considerable machining has to be done, besides more or less drilling, all of which is unnecessary with our improved wheel, since the felloes may be bought ready to be applied to the spiders, with all holes bored, and the spiders may be cast with their ends chamfered as described so that no machining is necessary. Furthermore, as the spokes are rimless when cast, there are no casting strains which result in serious loss by the breakage of wheels where they are cast in complete form. In our improved wheel even if the spokes should warp, which, however, is not likely to occur to any material extent owing to the shortness of the spokes, such warping makes no material difference. Our invention also makes practicable the use of a felloe of soft steel in connection with a spider or center of cast steel or wrought iron, with the result that a fairly light wheel of maximum strength is produced. Moreover, the spider may be applied to felloes of standard type, so that the complete wheel does not have an odd shaped felloe such as cast wheel manufacturers have found it necessary to use in order to cut down weight, and therefore our wheel is attractive and neat in appearance, which is an important consideration from a sales standpoint. In the drawings we have shown the spider as equipped with a felloe and rim of the demountable type, 11 indicating the demountable rim and 12 the tire carried thereby, but it should be understood that our invention is not limited to wheels provided with demountable rims, as any form of rim or felloe suitable for application to the spokes in the manner described comes within its scope. The hub portion of the wheel may be finished for the reception of a spindle in any suitable way, and the term "hub" as herein used is intended to refer generically to that portion of the wheel with which the inner ends of the spokes merge and by which they are connected together. The term "pressing" as used in connection with the effecting of the interlocking engagement between the rim and the spokes is intended to include either drawing, punching, or other equivalent means of projecting rim metal inwardly to lock the members of the wheel together.

It is to be observed that the spider is cast hollow and, in the form shown, has relatively thick short spokes. The wrought steel band 7, being of outwardly facing channel section, has great strength to resist bending stresses in addition to its ability to support a great load in tension and to resist crushing. As a result of the above recited relation of the parts, the forcing of the spider into the band or felloe, creates a wheel which is internally stressed without appreciably departing from the true circular shape. That is to say, the circular rim 7 maintain its circular form during the

pressing of the spider thereinto because of its own inherent strength to resist bending. The result is a finished round wheel.

It will be observed that by the construction herein shown there is no connection between the spider and the rim which can possibly put the spokes under tension. The relation of tension in the rim and compression in the spoke or spider is not departed from during the life of the wheel. 75

What we claim as our invention and desire to secure by Letters Patent, is—

1. The method of constructing a circular wheel which comprises, forming a rigid spider, forming a circular felloe of outwardly facing channel section and of relatively deep flanges and of an internal diameter smaller than the outer diameter of the spider, pressing the spider into the felloe to create a tension in the felloe not sufficient to substantially distort the form of the felloe, but great enough to hold the spider under compression for all loads within the capacity of the wheel. 85

2. The method of making a circular wheel which comprises, forming a circular wrought metal rim of a section having great strength in bending, said rim comprising a thin circular cylindrical inner peripheral wall and having relatively deep radially extending flanges, forming a spider comprising a hub and spokes, of an outer diameter larger than the inner diameter of the rim, forcing said spider laterally into the rim to put the rim under a tension and the spider under compression great enough to maintain the parts in such relation throughout the life of the wheel without substantially distorting the circular form of the rim. 90

3. The method of making a substantially circular finished wheel which consists in forming a circular wrought metal rim of a hollow section with a cylindrical inner wall and radially extending integral flanges having great strength in bending and tension, forming a spider having a hub and spokes of an outer diameter larger than the inner diameter of the rim, forcing said spider laterally into the rim to put the rim under tension and the spider under compression great enough to maintain the parts in such relation throughout the life of the wheel without appreciably deforming the circular contour of the rim, and then deforming the cylindrical inner wall of the rim to provide interlocking shoulders between rim and the spokes to prevent relative displacement of the spokes along the surface of the rim, said deformation further tensioning said inner wall. 110

4. The method of making a wheel which comprises forming a rigid spider consisting of a hub and spokes, forming a circular felloe of channel section with relatively deep flanges, and then forcing the spider laterally into the felloe. 125

5. The method of making a wheel which 130

comprises casting a spider consisting of a hub and spokes, forming a wrought metal circular felloe of outwardly facing, relatively deep channel section, and then pressing the spider laterally into the felloe.

6. The method of making a wheel which comprises forming a rigid spider consisting of a hub and spokes, forming a circular felloe of outwardly facing channel section with flanges deep enough to maintain the felloe circular when the spider is forced thereinto and then forcing the spider laterally into the felloe to tension the felloe.

7. The method of making a wheel which comprises forming a rigid spider consisting of a hub and spokes, forming a circular felloe of outwardly facing channel section with flanges deep enough to maintain the felloe circular when the spider is forced thereinto and then forcing the spider laterally into the felloe to tension the felloe, then deforming a part of the walls of the channel into interlocking engagement with the spokes and simultaneously increasing the tension in said felloe.

8. The method of making a wheel which comprises forming a rigid spider consisting of a hub and hollow spokes, forming a circular felloe of channel shape with flanges deep enough to maintain the felloe circular, forcing the spider laterally into the felloe to tension the same, and pressing the web of the channel into the ends of the spokes to provide interlocking shoulders and to increase the tension in the felloe.

9. The method of making a wheel which comprises forming a rigid spider comprising a unitary hub and spoke structure with the outer ends of the spokes separated relatively widely, forming a continuous circular felloe of channel shape and of slightly less internal diameter than the diameter of the spider and of an inherent strength in bending great enough to maintain the felloe in substantially true circular shape under the thrust of the spokes of the spider and introducing the spider under compression into the rim under tension.

10. The method of making a wheel which comprises forming a unitary spider comprising a hub and spokes rigid therewith, forming a continuous circular felloe of hollow substantially rectangular shape with a cylindrical web and integral relatively deep radially extending flanges, assembling the felloe upon

the unitary spider and simultaneously tensioning the felloe and compressing the spider.

11. The method of making a wheel which comprises forming a spider comprising a hub and spokes integral therewith, forming a continuous circular felloe of hollow substantially rectangular shape with a cylindrical web and integral relatively deep, radially extending flanges, assembling the felloe upon the spider and simultaneously tensioning the felloe and compressing the spider, then deforming the web of the felloe to provide shoulders interlocking with the spokes and by said deformation further tensioning said web.

12. The method of making a wheel which comprises forming a spider comprising a hub and hollow ended spokes integral therewith forming a continuous circular felloe of hollow substantially rectangular shape with a cylindrical web and integral radially extending flanges of a substantial depth, assembling the spider under compression within the rim under tension and pressing projections from the walls of the web into the ends of the spokes and by such pressing of projections increasing the tension of the felloe.

13. The method of making a metal wheel which comprises casting a hollow spider having a hub and integral spokes with pads upon the outer ends thereof, forming a rolled endless felloe of outwardly facing channel section with relatively deep radial flanges, pressing the spider laterally into the felloe to tension the felloe and bring the spider under compression, and then indenting the web of the channel into the ends of the spokes to form interlocking projections and to increase the tension on the felloe.

14. The method of making a wheel which comprises forming a unitary spider comprising a hub with spokes integral with the hub, forming a continuous circular rim of outwardly facing channel section and having integral relatively deep radially extending flanges, said rim having an internal diameter slightly less than the external diameter of the spider to secure the desired tension in said rim and compression in the spider when the rim is assembled on the outside of said spider, and then introducing the unitary spider laterally into the rim.
